PROCESS FOR CONTROL OF PRODUCT DENSITY OF SPRAY-DRIED DETERGENT COMPOSITIONS

Richard K. Flitcraft and William B. Satkowski, Wakefield, Paul J. Schauer, Danvers, and Raymond L. Liss, North Reading, Mass., assignors to Monsanto Chemical Company, St. Louis, Mo., a corporation of Delaware

No Drawing. Application December 20, 1955
Serial No. 554,137

14 Claims. (Cl. 252—116)

This invention relates to the preparation of controlled density spray-dried detergent compositions. More specifically the process of this invention relates to the preparation of low-sudsing, spray-dried detergent compositions containing a non-ionic active constituent and a plurality of alkaline builder components from the group comprising tetrasodium pyrophosphate, sodium tripolyphosphate, sodium carbonate, sodium bicarbonate, the sodium silicates, and the like, wherein a uniform product density is assured by the addition of a small amount of potassium or sodium soaps of higher fatty acids and resin acids to the detergent slurry prior to spray drying said composition.

The low-sudsing, spray-dried detergent compositions involved in the instant invention have been large volume commercial products for a number of years and their consumption is measured in millions of pounds per year. This large production of material is marketed in relatively small cartons, as for example, the nineteen-ounce and three-pound package, which are familiar to the home consumer. It is essential that the weights be true with good measure to provide for minor variations with change of equilibrium moisture during the interval between production and ultimate consumption. Modern packaging equipment is well adapted to the task, but those based on the principle of metering by fixed volume are critically dependent on the necessity that the products have a substantially constant bulk density. On the other hand packaging equipment based on the principle of metering by weight also requires that the product have a substantially uniform bulk density, since it is apparent that the package itself is of fixed volume. To design the package to contain the labeled quantity of product at its minimum bulk density would assure always being able to get the proper weight of material into the package, but the major portion of production of optimum bulk density would leave an undesirable amount of freeboard, or outage, in the package, and during periods of maximum bulk density the amount of freeboard would be so large as to cause the consumer to erroneously believe that she was getting short measure and for the same reason would cause difficulties with packaging regulations. The "freeboard," or "outage," is a measure of the fullness of the package and is the measure of empty space at the top of the package, normally indicated as the linear measurement of the distance between the top-level surface of the product and the top of the package.

The freeboard has heretofore been controlled to remain within permissible limits by various combinations of processing variables, as for example, changing the spray tower operating conditions such as drying temperature employed, spray pressure, type of spray nozzles, etc., and various slurry treatments prior to spray drying such as altering the solids content, altering slurry milling time, altering aging time of slurry, altering temperature-time history of slurry, etc. Whereas a new combination of processing conditions tended to give a partial control, this solution to the problem was not a true control, since un-

2

predictable results were often obtained. Thus it was not unusual to have to store off-grade material that was outside the acceptable bulk density specification, which meant the added expense of storage and handling of the off-grade material and classifying in a manner which would permit later gradual blending off of the material where it could be used to modify subsequent production and the blended mixture had an apparent density within the specifications. Accordingly, a simple, economical, and efficient means to control the density of the product became a critical problem.

The principal object of this invention is to provide an efficient means of controlling the bulk density of low-sudsing, spray-dried detergent compositions within prescribed narrow limits. Another object of this invention is to produce a uniform low-sudsing, spray-dried detergent composition, which can be packaged directly at the conclusion of the normal manufacturing operations without storing and blending off in subsequent operations. Still another object of this invention is to provide an economical process whereby a controlled-density detergent composition can be prepared by altering a single variable in a predictable manner rather than altering a combination of variables which have heretofore often responded in an unpredictable manner.

It has now been found that the addition of up to about 1 percent of a potassium or sodium soap to the non-ionic detergent slurry composition before spray drying provides a suitable means for controlling the bulk density of the spray-dried product without altering the desirable properties of the formulation. Preferably from about 0.3 to about 0.5 percent of the soap is employed to obtain the desired bulk density of about 0.28 to about 0.30 g./cc. The aforesaid quantity of soap is based on the amount of dry soap which is added to the detergent slurry composition. The soap may be added as an aqueous solution, gel or paste generally containing from about 30 to about 75 percent soap. The actual physical characteristics of the material will vary with the particular soap and concentration selected, but a liquid solution is generally preferred such that the soap can be readily metered into the detergent slurry. Preferably detergent compositions prepared for spray drying operations contain from about 55 to about 60 percent total solids, therefore on a dry basis the preferred amount of soap will be from about 0.5 to about 0.9 percent of the anhydrous mixture.

The detergent compositions can be directly made up with the full amount of the soap necessary to produce the desired density. However it is often advantageous, especially when the detergent composition is formulated from a different lot of active material, to initially add only a portion of the soap to the detergent slurry and then add the balance of the soap necessary to produce the desired bulk density as determined by the properties of the product obtained from the first portion of the drying operation for the particular batch of slurry.

The soaps include the potassium and sodium salts of the higher fatty acids, i.e., those containing from 12 to 18 carbon atoms, and the resin acids, e.g., lauric acid, myristic acid, palmitic acid, stearic acid, oleic acid, linoleic acid, abietic acid, pyroabietic acid, dehydroabietic acid, dihydroabietic acid, l-sapic acid, d-pimamic acid, agathic acid, etc., or the soaps can be prepared directly from the whole oils predominantly containing the aforesaid acids, e.g., tall oil, coconut oil, palm kernel oil, palm oil, olive oil, cottonseed oil, linseed oil, peanut oil, soybean oil, corn oil, castor oil, hydrogenated marine oil, and the like. Potassium tallate is the preferred soap since it is readily available, it is derived from one of the more economical sources of organic acids, and its composition is particu-

larly compatible and effective for the non-ionic detergent slurry compositions.

The potassium tallate is prepared by the neutralization of the tall oil in a solution of potassium hydroxide. Accordingly, the term "potassium tallate" as employed herein is defined to mean the tall oil acids potassium soap composition. Preferably the potassium tallate is obtained as liquid containing 30 to 35 percent potassium tallate, which material can be readily incorporated into the detergent slurry.

Tall oil is a well known article of commerce, obtained as a by-product of the sulfate pulp industry, essentially comprising a mixture of unsaturated and saturated fatty acids and rosin acids. Tall oil is thus by nature subject to considerable variation in composition being in part dependent on the species of wood processed, the season of the year the tree was felled, the age of the tree, the storage life of the wood, the procedure for processing the chips and converting the black liquor into tall oil, etc. Thus the average analysis of tall oil from fifteen mills ranged from 36 to 54 percent fatty acids, 38 to 58 percent rosin acids, and 6 to 18 percent unsaponifiable material. The fatty acids of tall oil are primarily unsaturated fatty acids, principally oleic and linoleic in substantially equal amounts, with a small content of saturated fatty acids, predominantly palmitic. Abietic acid is the predominant rosin acid of tall oil. Whereas solvent refined tall oil is preferred for the preparation of potassium tallate crude tall oil may be employed, but may tend to impart an off-white color and an odor to the spray-dried detergent composition. Other grades of tall oil, such as distilled tall oil, can be employed as desired.

The improved process of this invention may be generally employed in spray drying detergent compositions which are based on a non-ionic active constituent and a plurality of alkaline builder components from the group comprising tetrasodium pyrophosphate, sodium tri-polyphosphate, sodium carbonate, sodium bicarbonate, the sodium silicates, and the like. The non-ionic active constituent is generally a condensation product of the lower alkylene oxides containing up to 4 carbon atoms, for example, ethylene oxide, propylene oxide, butylene oxide, and mixtures thereof, with a compound, or compounds, having one or more active hydrogen atoms, as for example, aliphatic mercaptans, alkyl phenols, fatty acids, alcohols, and the like, which compounds preferably have a molecular weight of less than about 400. The mole ratio of alkylene oxide to active-hydrogen-containing compound is from about 3 to about 20 and preferably from about 9 to about 15. Illustrative detergent compositions are disclosed, for example, in U.S. Patents No. 2,522,446, 2,522,447, 2,550,691, 2,572,805, and 2,594,453.

The detergent compositions disclosed in U.S. Patent No. 2,550,691 are particularly suitable to the process of this invention. The detergent slurry is generally formulated to contain from about 45 to about 60 percent by weight total solids, and preferably from about 55 to about 60 percent by weight total solids, which on an anhydrous basis can be selected from the following illustrative compositions, all parts being by weight:

	Parts
Condensation product of tall oil with ethylene oxide in the ratio of 0.5:2.3 per part of tall oil	10-25
Tetrasodium pyrophosphate, sodium tripolyphosphate, or mixtures thereof	20-60
Sodium silicate, $Na_2O:SiO_2$ ratio of 1:2 to 1:3.2	6-25
Starch	0-20
Alkaline material selected from the class consisting of sodium carbonate, sodium bicarbonate and mixtures thereof	10-25
To the above product may be added from 0.1 to 5 parts of carboxymethyl cellulose.	

Other more specific illustrative compositions, are as follows, all parts being by weight:

	Parts
5 Condensation product of one part of tall oil with 1.6 parts of ethylene oxide	15.00
Tetrasodium pyrophosphate	40.00
Soda ash	20.25
10 Sodium silicate ("GC" silicate) $Na_2O:SiO_2=1:2$	24.00
Carboxy methyl cellulose	0.75

	Parts
Condensation product of one part of tall oil with 1.8 parts of ethylene oxide	20
15 Sodium tripolyphosphate	40
Sodium carbonate	15
Sodium silicate $Na_2O:SiO_2=1:3.2$	10
Starch	14
Carboxy methyl cellulose	1

	Parts
Condensation product of one part of tall oil with 2.0 parts of ethylene oxide	15.00
Tetrasodium pyrophosphate	40.00
25 Soda ash	20.15
Sodium silicate solution (water glass, 38% solids, 62% water) $Na_2O:SiO_2=1:3.2$	24.00
Carboxy methyl cellulose	0.75
Perfume	0.10

	Parts
Condensation product of one part of tall oil with 1.6 parts of ethylene oxide	15
35 Sodium tripolyphosphate	20
Tetrasodium pyrophosphate	20
Soda ash	20
Sodium silicate solution (38% solids) $Na_2O:SiO_2=1:3.2$	24
Sodium carboxy methyl cellulose	1

40	Following the preparation of the desired aqueous detergent slurry the soap is added thereto and mixed therein to provide a homogeneous slurry. The amount of soap necessary to obtain the desired bulk density of the spray-dried product will vary depending on slurry formulation modifications, the particular non-ionic active employed and its past history, such as age, storage conditions, treatment, etc., but up to about 1 percent by weight, based on the weight of the detergent slurry composition, has been found to be suitable. For greater ease of control it is preferred that the non-ionic active employed be freshly prepared and treated in a uniform manner. However non-uniform lots of active can also be readily employed in the process of this invention by initially adding only a portion of the amount of soap required when a freshly prepared active is employed, and thereafter adding additional increments thereof, as necessary, during the spray drying operation.
45	The following examples are illustrative of the process of this invention.
50	A series of batches of detergent slurries containing about 55 percent solids and essentially consisting of formulation D, shown above, were prepared, varying amounts of potassium tallate, as a heavy paste containing 75 percent solids, were added thereto, and reduced to a homogeneous mixture. The slurries were continually agitated to maintain a uniform composition throughout the drying operation and held at a temperature of about 45-50° C. The slurries were pumped to the spray nozzles of the drying tower and atomized at a nozzle pressure of about 500 p.s.i. into the hot gas (320-325° C.) of the spray chamber and dried in the usual manner employed in spray drying operations well known to the art. Each of the batches of slurry were treated under as nearly identical conditions as possible, such that the only variable was the quantity of potassium tallate pres-
55	

ent in the formulation. The spray-dried detergent compositions were found to vary in bulk density as shown in the following table.

Example	Percent Potassium Tallate Added		Density of Spray-Dried Product (g./cc.)	Parts
	Slurry Basis	Dry Basis		
1	None	None	0.40-0.42	
2	0.22	0.40	0.33	
3	0.31	0.56	0.30	
4	0.42	0.75	0.28	
5	0.65	1.17	0.25	

In addition to the essential components shown in the formulations listed above, minor quantities of other materials can be added as desired, for example a fluorescent dye, perfumes, etc. The perfume is of course added to the dried product to preclude loss in the drying operation. The spray-dried product can also be further treated as disclosed in the copending application of Paul J. Schauer, Serial No. 513,580, filed June 6, 1955, or by other procedures known to the art.

We claim:

1. In the process of manufacturing a spray-dried detergent composition, the steps which comprise the formulation of an aqueous detergent slurry, containing from about 45 to about 60 percent total solids, of a non-ionic active constituent and a plurality of alkaline builder components, wherein the non-ionic active detergent constituent is a condensate of an active-hydrogen-containing compound having a molecular weight of less than about 400 and a lower alkylene oxide containing up to 4 carbon atoms, the alkylene oxide to active-hydrogen-containing compound mole ratio being from about 3 to about 20 and the detergent composition on a solids basis consists of the following components, wherein all parts are parts by weight: 10 to 30 parts of non-ionic active constituent, 20 to 60 parts of alkaline phosphate builder salts, 10 to 40 parts of non-phosphate builder salts, up to 25 parts sodium silicate, up to 25 parts starch, and 0.1 to 5 parts of carboxy methyl cellulose; the addition of up to 1 percent, by weight of the detergent slurry composition of a soap selected from the group consisting of potassium and sodium salts of the higher fatty acids containing from 12 to 18 carbon atoms, the resin acids, and mixtures thereof to the said slurry; and spray drying said slurry; whereby the bulk density of the spray-dried detergent composition varies as an inverse function of the quantity of soap employed.

2. In the process of manufacturing a spray-dried detergent composition, the steps which comprise the formulation of an aqueous detergent slurry, containing about 45 to about 60 percent total solids, of a non-ionic active constituent and a plurality of alkaline builder components, wherein the non-ionic active detergent constituent is a condensate of an active-hydrogen-containing compound having a molecular weight of less than about 400 and a lower alkylene oxide containing up to 4 carbon atoms, the alkylene oxide to active-hydrogen-containing compound mole ratio being from about 3 to about 20 and the detergent composition on a solids basis consists of the following components, wherein all parts are parts by weight: 10 to 30 parts of non-ionic active constituent, 20 to 60 parts of alkaline phosphate builder salts, 10 to 40 parts of non-phosphate builder salts, up to 25 parts sodium silicate, up to 25 parts starch, and 0.1 to 5 parts of carboxy methyl cellulose; the addition of up to 1 percent, by weight of the detergent slurry composition, of potassium tallate to the said slurry; and spray drying said slurry; whereby the bulk density of the spray-dried detergent composition varies as an inverse function of the quantity of potassium tallate employed.

3. The process of claim 2, wherein the aqueous detergent slurry consists of from about 45 to about 60

percent total solids, which on an anhydrous basis comprises the following components, all parts being by weight:

		Parts
5	Condensation product of tall oil with ethylene oxide in the ratio of 0.5:2.3 per part of tall oil	10-25
	Tetrasodium pyrophosphate, sodium tripolyphosphate, and mixtures thereof	20-60
	Sodium silicate, $\text{Na}_2\text{O}:\text{SiO}_2$ ratio of 1:2 to 1:3.2	6-25
10	Alkaline material selected from the class consisting of sodium carbonate, sodium bicarbonate and mixtures thereof	10-25
	Carboxy methyl cellulose	0.1-5

4. The process of claim 2, wherein the aqueous detergent slurry consists of from about 45 to about 60 percent total solids, which on a solids basis comprises the following components, all parts being by weight:

		Parts
15	Condensation product of one part of tall oil with 1.8 parts of ethylene oxide	20
	Sodium tripolyphosphate	40
	Sodium carbonate	15
	Sodium silicate $\text{Na}_2\text{O}:\text{SiO}_2=1:3.2$	10
	Starch	14
25	Carboxyl methyl cellulose	1

5. The process of claim 2, wherein the aqueous detergent slurry consists of from about 45 to about 60 percent total solids, which on a solids basis comprises the following components, all parts being by weight:

		Parts
30	Condensation product of one part of tall oil with 2.0 parts of ethylene oxide	15.00
	Tetrasodium pyrophosphate	40.00
	Soda ash	20.15
35	Sodium silicate solution (water glass, 38% solids, 62% water) $\text{Na}_2\text{O}:\text{SiO}_2=1:3.2$	24.00
	Carboxyl methyl cellulose	0.75
	Perfume	0.10

6. The process of claim 2, wherein the aqueous detergent slurry consists of from about 45 to about 60 percent total solids, which on a solids basis comprises the following components, all parts being by weight:

		Parts
40	Condensation product of one part of tall oil with 1.6 parts of ethylene oxide	15
	Sodium tripolyphosphate	20
	Tetrasodium pyrophosphate	20
	Soda ash	20
50	Sodium silicate solution (38% solids) $\text{Na}_2\text{O}:\text{SiO}_2=1:3.2$	24
	Sodium carboxyl methyl cellulose	1

7. The process of claim 3, wherein the addition of potassium tallate consists of from about 0.3 to about 0.5 percent by weight of the slurry composition:

8. The process of claim 3, wherein the aqueous detergent slurry contains the following components in parts by weight:

		Parts
60	Condensation of one part of tall oil with 1.6 parts of ethylene oxide	15.00
	Tetrasodium pyrophosphate	40.00
	Soda ash	20.25
65	Sodium silicate $\text{Na}_2\text{O}:\text{SiO}_2=1:2$	24.00
	Carboxyl methyl cellulose	0.75

9. The process of claim 4, wherein the detergent slurry contains from about 55 to about 60 percent by weight total solids, and the addition of potassium tallate consists of from about 0.3 to about 0.5 percent by weight of the slurry composition.

10. The process of claim 5, wherein the detergent slurry contains from about 55 to about 60 percent by weight total solids, and the addition of potassium tallate

consists of from about 0.3 to about 0.5 percent by weight of the slurry composition.

11. The process of claim 6, wherein the detergent slurry contains from about 55 to about 60 percent by weight total solids, and the addition of potassium tallate consists of from about 0.3 to about 0.5 percent by weight of the slurry composition.

12. The process of claim 7, wherein the detergent slurry contains from about 55 to about 60 percent by weight total solids.

13. The process of claim 8, wherein the detergent slurry contains from about 55 to about 60 percent by weight total solids, and the addition of potassium tallate consists of from about 0.3 to about 0.5 percent by weight of the slurry composition.

14. The process of controlling the bulk density of a spray-dried, non-ionic active based detergent composition, comprising the formulation of an aqueous detergent slurry, containing from about 45 to about 60 percent total solids, of a non-ionic active constituent and a plurality of alkaline builder components, wherein the non-ionic active detergent constituent comprises from about 10 to about 25 percent by weight on an anhydrous basis of the detergent composition and is a condensate of (A) an active-hydrogen-containing compound having a molecular weight of less than about 400 selected from the group

5 consisting of the higher fatty acids, resin acids, aliphatic mercaptans, alcohols, alkyl phenols, and mixtures thereof, and (B) a lower alkylene oxide containing up to 4 carbon atoms, the alkylene oxide to active-hydrogen-containing compound mole ratio being from about 3 to about 20; the addition thereto of up to 1 percent, by weight of the detergent slurry composition, of a soap selected from the group consisting of potassium and sodium salts of the higher fatty acids containing from 12 to 18 carbon atoms, the resin acids, and mixtures thereof to the said slurry; mixing said soap to provide a substantially homogeneous composition; and spray drying said slurry; wherein the bulk density of the spray-dried detergent composition is characterized by a value which varies as 10 15 an inverse function of the quantity of soap employed.
